UNITED STATES PATENT OFFICE.

ANDRÉ GARBARINI, OF COURBEVOIE, SEINE, FRANCE.

RADIATOR FOR GAS HEATING BY INCANDESCENCE.

1,427,371.

Specification of Letters Patent. Patented Aug. 29, 1922.

Application filed April 22, 1922. Serial No. 556,111.

To all whom it may concern:

Be it known that I, ANDRÉ GARBARINI, engineer, citizen of the Republic of France, residing in Courbevoie, Seine, France, and whose post office address is 23 Rue de Colombes, have invented certain new and useful Improvements in Radiators for Gas Heating by Incandescence; and I do hereby declare the following to be a full, clear, and 10 exact description of the invention, such as will enable others skilled in the art to which it appertains to make and use the same, reference being had to the accompanying drawings, and to letters or figures of reference 15 marked thereon, which form a part of this specification.

This invention relates to improvements in the construction of radiators for gas heating by incandescence making use of a gas mantle 20 of the type known as inverted mantle, which is placed in the horizontal position at the focus of a parabolic mirror.

To provide for the proper working of such radiators, it is very important that the mantle should be disposed on the axis of the 25 mirror and maintained in an elastic manner. For this purpose the claws of the ring carrying the mantle are well fitted upon plane surfaced lugs formed upon the steatite or 30 porcelain burner and are held in an elastic manner in this position by the pressure of a metal ring acted upon by a spiral spring.

The use of the ordinary inverted burners placed horizontally in heating apparatus 35 does not give quite the desired results as concerns the heating action, because the gas and air mixture rises for the greater portion to the upper part of the mantle which will become overheated while the lower parts are 40 only slightly heated, thus showing an irregular incandescence on the surface of the mantle. In order to obtain a regular incandescence upon the whole surface of the mantle, the latter is mounted upon a burner whose 45 gas mixture outlet end is provided with holes at the upper part, whilst the lower part is bevelled, so as to cause the greater part of the gas mixture to proceed to the lower parts of the mantle, thereby producing the complete 50 incandescence of the mantle. Furthermore, the gas and air mixture should be properly adjusted in order to provide for the emission of red or infra-red rays which give the maximum calorific efficiency, and 55 for this purpose the mantle is also construct-

ed with meshes which are wide as well as thick.

Other improvements in the construction of these radiators will be set forth hereunder.

60

In the accompanying drawings:

Fig. 1 is a side view, partly in section, of the whole radiator.

Fig. 2 is a front view of the same.

Fig. 3 is a longitudinal section on a larger 65 scale shewing the air and gas supplying element, the burner and the special mounting of the gas mantle.

Figs. 4 and 5 are also vertical sections on a larger scale of the jointed supporting base. 70 Fig. 6 is an end view of the burner.

The radiator comprises a supporting base 1 whereon is pivoted at 2 an arm 3 which is secured to the parabolic reflector 4. To the arm 3 is secured the nib 5 which serves to 75 connect the flexible gas admission tube, the gas passing through a cock 6 and proceeding thence to the regulating chamber through the small tube 7. The disposition of the nib 5 adjacent the joint 2 of the reflector will 80 produce only a slight movement of the flexible tube in all positions of the reflector 4.

On the axis of the reflector and at the rear 85 of the latter is secured by means of screws a metal socket 8 wherein is engaged a tube 9 forming a mixing chamber at one end whereof is secured the porcelain or steatite burner 10. The tube 9 is fixed in position in the socket 8 by the set screw 11, and it is provided outside the socket 8 with a screw-thread 90 wherein is engaged the ring 12 used to regulate the air inlet through the holes 13. When the adjustment has been once determined, the said ring is locked in position by a set screw 14.

At the outer end of the tube 9 is situated the gas inlet tube 7 which opens into a small chamber 15 having an orifice 16 for the admission of the gas into the mixing chamber 9. The amount of gas to be admitted into 100 this chamber 9 is regulated by means of a screw needle 17 which is locked in position by a set screw 18 after the regulating has been performed.

The gas mantle 19 which is made with 105 wide and thick meshes, is mounted in the usual manner upon a steatite support 20 comprising three attaching claws 21 adapted to engage in the rear of the lugs 22 having a plane surface, against which they are held 110

in an elastic manner and well in the axis of the reflector by means of a cylindrical ring 23 acted upon by a spiral spring 24 disposed within the socket 8 and at the exterior of 5 the mixing chamber 9.

The burner 10 which is screwed to the end of the mixing chamber 9 is provided at the outer end and near the top with small holes 25 covering about half its surface,

10 whilst the lower part 26 is cut on a bevel so as to cause a considerable quantity of the mixture to proceed toward the lower part of the mantle whereby the same shall be made incandescent upon the whole surface, which 15 result would not be obtained were the mixture obliged to flow through holes distributed in an irregular manner upon the entire surface of the burner, as the mixture always tends to rise to the upper part of the mantle.

20 The latter is preferably provided with a small piece of platinum or palladium sponge for the automatic ignition upon opening the gas inlet.

The supporting base 1 of cast metal, for 25 example of aluminium, is provided with two lugs 27, Figs. 4 and 5, which are rendered elastic by a saw cut 28 in the head of the support. They are connected by the pintle 2 whereon is pivoted the arm 3 supporting 30 the reflector, which is preferably of cast aluminium. To obviate gripping action, the surfaces of the arm 3 engaging the lugs 27 are faced with washers 29 of a different metal, brass for example, which are inserted 35 in the same.

The supporting base is also provided at the bottom part with a hole 30 whereby it may be placed against the wall by engaging the said hole with a suitable wall hook, 40 and is also provided with a hole 31 with gas tap for ceiling suspension by screwing upon a suitable connecting member.

The reflector 4 is provided at the front part with crossed protectors 32 in flat metal 45 which are hooked to the beaded rim of the reflector and are twisted so as to afford but a slight thickness in the direction of the heat rays.

Having now described and ascertained the 50 nature of my said invention and in what manner the same is to be performed, I declare that what I claim is:—

1. A radiator for gas heating by incandescence comprising: a parabolic mirror; a device to carry this mirror; a gas mantle of the inverted type disposed at the focus of the parabolic mirror; a burner with refractory nozzle fixed at the middle of the mirror; lugs on the said refractory nozzle; claws 55 on the mantle holding ring to engage the said lugs; elastic means to hold the claws exactly flatwise against the lugs of the nozzle.

2. A radiator for gas heating by incandescence comprising: a parabolic mirror; a

device to carry said mirror; a gas mantle of the inverted type disposed at the focus of the parabolic mirror; a burner with refractory nozzle fixed at the middle of the mirror; lugs on the said refractory nozzle; claws on 70 the mantle holding ring to engage the said lugs; a metal ring pressing against the lugs; and a spiral spring pressing against the said metal ring.

3. A radiator for gas heating by incandescence comprising: a parabolic mirror; a device to carry said mirror; a gas mantle of the inverted type disposed at the focus of the parabolic mirror; an annular member fixed upon the back wall of the mirror at 75 the centre of said mirror; a tubular mixing chamber in said annular member, provided with holes for the admission of the air; screw ring adapted to close more or less said holes; a gas chamber at the end of the mixing chamber, with a gas inlet orifice; an adjustable screw needle controlling said gas orifice; a refractory nozzle fixed at the end of the mixing chamber; lugs on the said nozzle; claws on the mantle holding ring to 90 engage the said lugs; a metal ring pressing against the lugs; and a spiral spring located in the annular member to press against the said metal ring.

4. A radiator for gas heating by incandescence comprising: a parabolic mirror; a device to carry said parabolic mirror; a gas mantle of the inverted type disposed at the focus of the parabolic mirror; an annular member fixed upon the back wall of the 95 mirror; a tubular mixing chamber in said annular member provided with holes for the admission of the air; a screw ring adapted to more or less close said holes; a set screw to lock the screw ring in position; a gas chamber at the end of the mixing chamber with a gas inlet orifice; an adjustable screw needle to control said gas orifice; a set screw to lock this needle in position; a refractory nozzle fixed at the end of the mixing chamber; lugs on the said nozzle; claws on the mantle holding ring to engage the said lugs; elastic means located in the annular member to hold the claws exactly flatwise against the lugs of the nozzle.

5. A radiator for gas heating by incandescence comprising: a parabolic mirror; a device to carry the said mirror; a gas mantle of the inverted type disposed at the focus of the mirror; an annular member fixed 120 upon the back wall of the mirror; a tubular mixing chamber in said annular member; a refractory nozzle with bevelled and apertured lower part fixed at the end of the mixing chamber; a gas chamber at the other end of the mixing chamber; lugs on the refractory nozzle; claws on the mantle holding ring to engage said lugs; and elastic means to hold the claws exactly flatwise against the lugs of the nozzle.

6. A radiator for gas heating by incandescence comprising: a parabolic mirror; a lug fixed to said mirror; a base pivoted on said lug; a gas inlet piping on the said lug; a gas mantle of the inverted type disposed at the focus of the parabolic mirror; a burner with refractory nozzle fixed at the middle of the mirror; a connecting gas pipe between the inlet piping of the lug of the base and the burner; lugs on the said refractory nozzle; claws on the mantle holding ring to engage the said lugs of the nozzle; and elastic means to hold the claws against the lugs of the nozzle. 10
- 5 In testimony that I claim the foregoing as my invention, I have signed my name. 15

ANDRÉ GARBARINI.
